UNITED STATES PATENT OFFICE

ALFRED WILLIAM BENNIS, OF BOLTON, ENGLAND

FURNACE GRATE

Application filed March 14, 1929, Serial No. 347,068, and in Great Britain March 14, 1928.

The present invention relates to furnace grates and more particularly of the chain grate type.

Under modern conditions of combustion, particularly with regard to electricity supply station practice the use of heated air for the air supply to the furnace is demanded and as a consequence of the passage of the heated air between the grate bars or through said grate bars or their air spaces and also as a consequence of the high temperature furnace conditions above the grate, these are liable to become overheated, causing them to deteriorate, crack and eventually burn away. A further detrimental feature arises in that when the fire bars become heated in chain grates, the fuel tends to cake on the bars which produces a condition known as cauliflowering, with the result that the efficiency of combustion is impaired and the output is reduced with the result that the furnace has to be slowed down and the grate cooled.

The tendency of modern conditions is to continually demand higher air temperature supply to the furnace, and it is extremely likely that as time goes on an air supply of even greater temperature will be required.

With a view to meeting these demands, the object of the present invention is to provide means whereby links or fire bars of the grate may be kept cool independently of the temperature of the air supply through the grate so that while in use the grate is rendered substantially unburnable.

Accordingly to the present invention one or more air passages are provided in the grate bars, a connection being formed between the inlet of said air passages and a cool air chamber below the grate bars, whilst the exit of the air passage or passages is connected to a warm air compartment or chamber substantially adjacent the cool air compartment.

Means are provided for conducting cool air to the cool air compartment and for taking off the warm air from the warm air compartment. In the latter case, the warm air taken off may be utilized for combustion purposes.

In a preferred form of construction, the

grate bars are mounted on hollow carrier bars which are divided into a plurality of compartments by suitable diaphragms or divisions. One or more of these compartments is utilized for the transmission of cool air from the source to the air passages in the grate bars whilst the heated air, after its passage through the grate bars, travels through the hot air compartment or compartments of the hollow carrier bars whereupon the heated air is then taken through the grate to assist combustion or through hollow furnace walls and thence to the combustion chamber or further to air heaters to be further heated and then utilized for combustion.

Any suitable form of connection may be used between the grate bars and the carrier bars. Preferably these connections are in the form of tubes extending between the ends of the passages in the grate bars and the orifices in the carrier bar.

The air may be forced by a fan or the like means through the cool air compartments of the hollow carrier bar and then through the links or grate bars in parallel after which it passes into the warm air compartment in the hollow carrier bars and thence on to trunks or conduits to air heaters after which it passes through said air heaters on to hot air trunks to the underside of the grate again where it passes up to burn the fuel on the grate.

Trunks or conduits may be arranged to convey the cool air to the moving hollow carrier bars from the cool air supply means, whilst additional trunks are utilized to convey the heated air away from the hollow carrier bars. No mechanical difficulty exists in this transfer of the air from the conduit to the hollow carrier bar or from the hollow carrier bar to the trunk as air has been fed to travelling chain grate compartments in a number of ways in the past.

It will be obvious that the hollow carrier bars may have more than one entrance for the cool air and more than one exit for the hot air.

The invention is more particularly described with reference to the accompanying drawings, in which—

Figure 1 is a plan view of a general arrangement of a grate constructed according to the present invention.

Figure 2 is a sectional elevation of the grate on the line B—B of Fig. 1.

Figure 3 is a transverse section of the grate along the line A—A of Fig. 2.

Figure 4 is a plan view on a larger scale, of a portion of the grate.

Figure 5 is an enlarged transverse section 10 of the grate across a portion of this only.

Figure 6 is a section through a portion of the longitudinal upper run of the grate.

Figure 7 is a transverse section of a portion 15 of a modified arrangement for supplying air to the grate bars.

Figure 8 is a sectional view through a grate bar and hollow carrier bar on which 20 said grate bar is mounted showing one method of interconnection between said grate bar and its carrier bar for the purpose of allowing air to pass through the grate bar.

Figures 9 and 10 show modified forms of 25 construction in which the grate bars are cast on tubes connected to the hollow carrier bars.

Figures 11, 12 and 13 are detail views of a 30 modified arrangement for the supply of air to the grate bars, Fig. 11 being a transverse section through the hollow carrier bar, Fig. 12 being a corresponding longitudinal view in elevation and Fig. 13 being a corresponding longitudinal view in plan.

Figures 14 and 15 show a modified arrangement for the air supply to the drop link 35 type of stoker, Fig. 14 being a transverse section across a portion of the upper run of the grate and Fig. 15 being a view in elevation over a portion of the longitudinal run of the grate. Figure 16 is a perspective view showing the various parts diagrammatically in 40 their relationship to one another.

In the general arrangement as shown in 45 Figs. 1-3 of the drawings, the inlet ducts for supplying cool air for passage through the grate bars are illustrated at 20 and the exit ducts through which the warm air is led away, preferably to assist in the combustion on the grate, are illustrated at 21, combustion air ducts being illustrated at 22.

It will be seen from a study of these drawings 50 that each duct 20 or 21 extends transversely preferably over the whole length of the grate. The top portion of the ducts 20 merge into a number of conduits 23 extending 55 over a portion of the length of the grate, whilst the tops of the ducts for the exit of the warm air extend into portions 24 also extending over a portion of the length of the grate. A number of carrier bars 25 each extending 60 transversely over the whole or a portion of the grate are shown at 25, whilst the rollers for supporting the carrier bars are illustrated at 26 in Fig. 2.

Turning to Figs. 4-6 of the drawings it 65 will be seen that each transverse carrier bar

is formed with a pair of compartments 27, 28 separated by a division wall or diaphragm 29.

A plurality of hollow grate bars 30 are mounted on each carrier bar. Various methods of mounting these grate bars on the carrier bars are illustrated in Fig. 6.

With regard to the manner in which the extreme left hand grate bar is mounted on its carrier bar, it will be seen that a plurality of lugs 31 are formed on the upper face of each hollow carrier bar 25 at spaced intervals along this, these lugs 31 being adapted to receive guides 32, the lower portions of which are bifurcated to rest on such lugs 31 70 whilst the upper portions of which are T-shaped to be engaged by T-shaped recesses in the grate bars. The grate bars are hollow as illustrated at 33, the passages through the grate bars being connected to the chambers 85 27 and 28 of the hollow carrier bars so that cool air supplied upwardly through the transverse cold air duct 20 passes into the longitudinally extended portion of such duct 23 and thence into chambers 27 of all those carrier bars situated above said longitudinally extended upper portion 23 of the cold air duct whereupon the cold air passes through the 90 grate bars 30 on said carrier bars and thence into the warm air compartment 28 of all those carrier bars, whereupon the air which has been warmed in its passage through the grate bars is exhausted into the longitudinally extended upper portion 24 of the transverse warm air duct 21. If desired, the warm air is then led 100 off to air heaters for further heating and to subsequently assist in supporting combustion of the fuel on the grate.

Any convenient arrangement may be adopted for mounting the grate bars on to the 105 transverse hollow carrier bars. A number of such arrangements are illustrated in Figs. 8-13.

In the construction according to Fig. 8 the 110 grate bars 34 have passages 35 formed therein, the inlet to such passage 35 being connected to a tube 36 whilst the exit of the passage 35 is connected to the tube 37.

The tube 36 further is connected with a cool air compartment 38 of a carrier bar 39 115 whilst the tube 37 is connected to the warm air compartment 40 of said hollow carrier bar.

These tubes 36, 37 may either be cast in or otherwise suitably secured to the carrier bar 39 and the opposite ends inserted just within the inlet and exhaust ends respectively of the passages 35, or alternatively such tubes may be cast with such grate bars 34 and their ends inserted, prior to use on the grate within the orifices formed in the upper face of the hollow carrier bar 39.

In the modified form of construction shown in Fig. 9 a hollow carrier bar 41 is provided of substantially triangular cross section, the 130

cool air compartment 42 being separated from the warm air compartment 43 by a vertical division wall or diaphragm 44.

In this construction grate bars 45 are utilized which are cast on tubes 46, such tubes inter-engaging with tubes 47 fitted to the cool and warm air compartments of the hollow carrier bar, so that air is allowed to pass from the cool air compartment 42 through the tubes 47 and tubes 46 of the grate bars mounted on such carrier bar and thence into the warm air compartment of such carrier bar.

In the further modified form of construction illustrated in Fig. 10 each grate bar 48 is cast on a tube 49, one end of which tube is inserted in the cool air compartment 50 of the hollow carrier bar 51 whilst the opposite end is inserted in the warm air compartment 52 of such carrier bar.

It will be seen that in the arrangements illustrated in Figs. 4-6 and Figs. 8-10, the cool air passes from the cool air compartment of each carrier bar through the grate bars mounted thereon in parallel and then passes to the warm air compartment of the carrier bar.

In the construction illustrated in Figs. 11-13 the cool air passes through a number of grate bars in series before returning to the warm air compartment of the carrier bar. By this, it is not meant to infer that the air passes through every grate bar on any single carrier bar in parallel prior to entering the warm air compartment of such carrier bar. Preferably, separate streams of cool air each pass through about six grate bars prior to entering the warm air compartment of the carrier bar.

In Figs. 11-13 the carrier bar is illustrated at 51 and its cool and warm air compartments at 52 and 53 respectively whilst the grate bars mounted on the carrier bar are illustrated at 54.

The air passes along a coiled tube 55 in series through a number of laterally adjacent grate bars 54, which are formed by casting the metal of the grate bars around the tube.

In a further modified form of construction (not illustrated in the drawings) the tube itself may form the hollow grate bar and for this purpose, is suitably shaped and treated.

It will be appreciated that in a very narrow grate one coil over each carrier bar may be sufficient in which case it would not be necessary for the carrier bar to be hollow, as means may be arranged at the inlet and outlet of the coil to feed to and from the cool and warm air ducts. In wider grates, however, it would be preferred to provide a number of series coils, the number depending on the coolness and speed of air passing therethrough for cooling purposes.

In Figure 16, the ash pit 10 has the grate above it, of which only the one carrier bar 25

is shown, with the one grate bar or link 30 thereon. The other figures of the drawings show that a large number of carrier bars, each with a great number of grate bars 30 may be employed. The carrier bar is substantially of the form shown in Fig. 8, with the central partition dividing it along its length into compartments 38 and 40. Air pumped from compressor 11 by motor M passes through the cold air duct 20 into the inlet trunk 23 which forms a manifold, and has an aperture in its upper surface. This aperture, it will be understood, is normally closed by a plurality of the bars 25. In this conventional figure, the carrier bar 25 has been shown away from its definite position, for greater clearness. The arrows indicate the flow of cold air from the compressor 11 through an opening 14 into the compartment 38 of the carrier bar 25. Each of the grate bars 30 has a passage 32 through it by which air may pass from the cool air compartment 38 into the hot air compartment 40. At the other end of the illustrated carrier bar 25, this hot air passes through the opening 15 and an aperture in the top outlet trunk or manifold 24 to the hot air duct 21. Thence the air moves through an air heater 12 shown conventionally as connected to the hot air pipe 13 leading to the opening 22 into the ash pit 10 whence the air moves upward between the various carrier bars 25 and grate bars 30 into the fire bed.

For the purpose of illustrating an arrangement which may be employed for adapting the present invention to the drop link type of stoker, reference is made to Figs. 14 and 15 of the drawings. In these figures the cold air inlet is illustrated at 56 and the hot air exit at 57.

Cold air passes from the inlet 56 up through a vertical conduit 58 and thence outwardly at 59 into passages 60 formed in links 61. The air is heated in its travel along the passages 60 and returns to a vertical conduit 62 and thence into the hot air exit 57.

It will thus be seen that cold air may be fed up through a vertical conduit situated between a plurality of laterally adjacent links or grate bars and emerges from these links or grate bars at the opposite ends thereof. In this way a single cold air inlet only is necessary for each pair of laterally adjacent groups of grate bars.

In the form of construction illustrated in Fig. 7 a longitudinal cold air duct 63 is provided as distinct from the transverse cold air ducts already described whilst similar remarks apply to the longitudinal hot air ducts 64, these ducts 63 and 64 being connected to vertical ducts or passages 65, 66 with the cold air compartments and hot air compartments respectively of the various carrier bars.

In order to prevent the heated air which is fed to the furnace or cells under the grate

from leaking into the cool air conduit grates, sliding joints or the like, air at a higher pressure is utilized in the conduit to the cool air compartments in the hollow carrier bar than is used under the grate.

5. A number of cool air conduits may be utilized to feed cool air to the hollow carrier bars so that such carrier bars may be fed with cool air at different pressures according to their position of travel along the furnace.

10. It will be obvious that the means for cooling the grate bars as described above may be combined with the air supply regulating means described in the specifications accompanying my patent applications Serial Nos. 311,169, filed October 8, 1928, and 334,772, filed January 24, 1929.

I declare that what I claim is:—

1. A furnace grate comprising stationary longitudinally directed and transversely spaced air inlet and outlet trunks having top apertures, hollow carrier bars operable to travel over said trunks and to substantially close said apertures and having bottom apertures positioned to register with the apertures of the trunks, hollow grate bars mounted on said carrier bars and communicating therewith so that air may pass between the cavities of said grate and carrier bars, means for supplying air to said inlet trunk, said inlet trunk and carrier bars and grate bars providing passages for the air therethrough to said outlet trunk, and means for withdrawing air from said outlet trunk.

35. 2. A traveling furnace grate comprising hollow carrier bars and hollow grate bars mounted thereon, each carrier bar containing a longitudinal partition dividing it into two compartments, means for placing the cavities of the grate bars mounted on the carrier bars in communication with each of said compartments, and means for supplying air to one of said compartments, the other of said compartments having an outlet.

50. 3. A traveling furnace grate comprising hollow carrier bars and hollow grate bars mounted thereon, each said carrier bar containing a longitudinal partition dividing it into two compartments, an air inlet conduit for delivering air into one compartment, an air outlet conduit for permitting the escape of air from the other compartment, and means for placing the cavities of the grate bars mounted on the carrier bars in communication at their ends with an inlet and an outlet compartment of said carrier bars.

55. 4. A traveling furnace grate comprising hollow carrier bars and pluralities of hollow grate bars mounted thereon, conduit means for connecting the grate bars of each plurality so that the air may flow in succession through the bars of such plurality, each carrier bar containing a longitudinal partition dividing it into two compartments, means for placing the cavity of the one end grate

bar of each plurality in communication with one said compartment and the cavity of the other end grate bar of each plurality in communication with the other said compartment, and means for supplying air to one of said compartments, the other of said compartments having an outlet.

5. A furnace as in claim 2 in which said communication means includes separable connections for the passage of air to and from each said carrier bar and grate, whereby the grate bars may be removed without disengagement of the carrier bars.

10. A furnace grate as in claim 2 in which the grate bars comprise tubes and fuel supporting structures formed upon the tubes, and the ends of each tube being connected to a carrier bar whereby to establish the communication of the cavity of the tube with the two compartments of the carrier bar.

15. A furnace grate as in claim 2 in which the grate bars are provided with tubes fixed thereto and extending relatively downwardly therefrom, and hollow connecting means are provided on the grate bars for engaging said tubes whereby to form said communication means between the cavities in said grate bars and said carrier bars.

20. A furnace grate comprising stationary air trunks extending lengthwise of the grate and having apertures on their upper surfaces, hollow carrier bars located above said air trunks and extending transversely of the grate and having bottom apertures in communication with said trunks through said trunk apertures and providing air inlet and outlet compartments alternately extending transversely of the grate, a plurality of hollow grate bars mounted on said carrier bars and in communication at their ends with the air inlet and outlet compartments thereof, and means for supplying air to one of said trunks wherefrom it may pass to the air inlet compartments, the other of said trunks having an outlet.

25. 9. A furnace grate comprising a plurality of hollow carrier bars and means for connecting the same to travel in chain to form a traveling furnace grate structure, a plurality of hollow grate bars for forming the fuel supporting surface of the grate mounted on each of said carrier bars, said carrier bars extending transversely of the grate and being provided with lengthwise internal partitions dividing them each into two compartments, each said hollow grate bar having connections to each of said compartments of the hollow carrier bar upon which the grate bar is mounted.

30. 10. A traveling furnace grate comprising hollow grate bars for forming the fuel supporting surface of the grate, fixed air inlet and outlet conduits extending along the grate, hollow members extending across the grate and providing air inlet and outlet comp-

ments in communication with said conduits, and connections for supporting said grate bars on said hollow members and including conduits for establishing communication between the cavities of the grate bars and said compartments so that air may flow from said inlet conduit through said inlet compartment and said grate bars to cool the said grate bars and be discharged therefrom through said outlet compartment and outlet conduit.

In witness whereof, I have hereunto signed my name this 26th day of February, 1929.

ALFRED WILLIAM BENNIS.
